UNITED STATES PATENT OFFICE.

LUCY M. BRETT, OF FOREST HILLS, NEW YORK, ASSIGNOR TO BRETT MANUFACTURING CO., OF NEW YORK, N. Y., A CORPORATION OF NEW YORK.

BANDEAU.

1,287,626.

Specification of Letters Patent. Patented Dec. 17, 1918.

Application filed April 10, 1918. Serial No. 227,628.

To all whom it may concern:

Be it known that I, LUCY M. BRETT, a citizen of the United States, and resident of Forest Hills, in the county of Queens and 5 State of New York, have invented certain new and useful Improvements in Bandeaux, of which the following is a specification.

The object of this invention is to provide a serviceable and ornamental bandeau of 10 simple, cheap and inexpensive construction which can be readily applied to or removed from the head of the wearer.

The invention, generally stated, comprises a body having a pliable metallic core 15 and a pliable non-metallic covering, the extremities of said body being bent back upon and secured to the main portion of the latter to form elongated loops which are adapted to be bent into hook-form and connected one 20 with the other when the device is applied to the head of the wearer.

The invention also comprises various features of construction which will be herein-after described and claimed.

25 In the drawings—

Figure 1 illustrates my improved bandeau as in actual use.

Fig. 2 is a front view, on a larger scale, of the looped ends of the device as hooked 30 together.

Fig. 3 is a rear view of one of the loop end portions.

Fig. 4 is a similar view of one end, with the free ribbon end removed to expose the 35 clip or staple connection.

Fig. 5 is an enlarged cross-section, as on the line 5—5 of Fig. 4.

My improved bandeau in the form selected for illustration, comprises a pliable non- 40 elastic body portion composed, preferably, of a central metallic core, 10, of soft copper or iron wire; a covering of rubber, 11, on the core; a covering of braided thread, 12, on the rubber, and a covering of spirally 45 wound ribbon, 13, on the braided thread. The ends of the body are bent inward and fastened upon the main part of the body, so as to form elongated loops, 14, which, by virtue of the pliable quality of the body, may 50 be variously fashioned in simulation of the loops of a bow. Likewise the body may be bent at or adjacent the inner ends of the loops to form oppositely-disposed hook-portions that may be readily connected one with 55 the other when the loops are brought to-

gether, as represented in Figs. 1 and 2. The free ends of the body are fastened in any suitable way to the main portion, preferably by clips or staples, 15, which embrace the exterior ribbon covering, 13, and serve 60 also to secure the free ends of the latter to the body. These ends, together with the clips or staples, are covered and concealed by pieces of ribbon, 16, or the like, knotted thereon, as at 17, so that the free ends of 65 the ribbon pieces extend loosely from the body, and thus, when the loops are hooked together, complete the general effect of a bow, as illustrated.

To apply the device above described it is 70 flexed about the head similarly to an ordinary head band, and the looped and hooked ends are then connected one with the other, thus effectually retaining the device firmly yet comfortably in place, as illustrated in 75 Fig. 1. When thus applied the device not only effectually keeps the hair of the wearer in place but it presents a neat and ornate appearance. By reason of the pliability of the device it can be readily adjusted upon 80 the head of the wearer at any desired angle, and the bow-like connection can be disposed at any preferred point as the taste of the wearer may suggest. The exterior ribbon covering and the bow ends may, of course, 85 be of any appropriate color desired.

I claim—

1. The herein described bandeau comprising a body having a pliable metallic core and a pliable non-metallic covering, the extremities of the said body being bent back upon and secured to the main part of the latter to form elongated loops adapted to be bent into hook-form and connected one with the other. 95

2. The herein described bandeau comprising a body having a pliable metallic core and a pliable non-metallic covering, the extremities of the said body being bent back upon the main part of the latter to form 100 elongated loops adapted to be bent into hook-form, and ribbon ends covering and concealing such extremities and presenting, in conjunction with the loops, a bow-like appearance when the loops are bent into 105 hook-form and connected one with the other.

3. The herein described bandeau comprising a body having a metal core, and a pliable non-metallic covering including a spirally-wound ribbon, the extremities of said 110

- body being bent back upon the main part of the latter to form elongated loops, means for fixedly fastening each of said extremities to the main part of the body, and ribbon ends covering and concealing the said extremities and fastening means and presenting, in conjunction with the loops, a bow-like appearance when the loops are bent into hook-form and connected one with the other.
- 10 4. The herein described bandeau comprising a body having a pliable metallic core and a pliable non-metallic covering including a spirally wound ribbon, the extremities of said body being bent back upon the main

part of the body to form elongated loops, 15 clips embracing and connecting said extremities and the adjacent parts of the body, and pieces of ribbon-like material covering and concealing the said extremities and clips, said material having loose ends which 20 present, in conjunction with the loops, a bow-like appearance when the loops are bent into hook-form and connected one with the other.

Signed at New York city, in the county of 25 New York and State of New York, this first day of April, A. D. 1918.

LUCY M. BRETT.
